Specification for Design.

Patented Dec. 20, 1921.

Application filed September 20, 1921. Serial No. 502,082. Term of patent 7 years.

To all whom it may concern:

Be it known that I, HARRY H. KEPLEY, a citizen of the United States, residing at Philadelphia, in the county of Philadelphia and State of Pennsylvania, have invented a new, original, and ornamental Design for a Novelty Figure, of which the following is a specification, reference being had to the accompanying drawing, forming part thereof.

Fig. 2 is a side view of the same.

Fig. 3 is a section on the line 3—3 in Fig. 1; and,

Fig. 4 is a section on the line 4—4 in the same figure.

I claim:

The ornamental design for a novelty figure as shown.

HARRY H. KEPLEY.
